UNITED STATES PATENT OFFICE

2,225,809

WINDOW

Frederick Pickering Walker, London, England, assignor to The Crittall Manufacturing Company, Limited, London, England

Application July 23, 1938, Serial No. 220,987
In Great Britain August 3, 1937

6 Claims. (Cl. 98—88)

This invention relates to sound reducing windows which are designed to admit air for ventilation but baffle sound waves.

According to this invention, a sound reducing window having a plurality of panels or of groups of panels arranged in three or more parallel planes, comprises one or more hinged panels in at least one of the outer planes and a horizontally sliding adjustable panel or panels in at least one, 10 and preferably in one or more of the planes, the sliding panel or panels being capable of adjustment to a position providing a gap or gaps, staggered in relation to the opening or openings obtained when the hinged panel or panels is or are 15 opened.

In practice it will be found most convenient to arrange the hinged panels respectively on the interior and exterior planes with the sliding panels in the intermediate plane or planes.

20 It will be appreciated that the window of this invention provides a wide range of control as regards the extent of ventilation while reducing appreciably the amount of sound that can pass through the window opening.

25 In the drawings:

Figures 1 to 5 and 7 to 10 are diagrammatic sectional plan views of several forms of window comprising a plurality of panels located in three parallel planes, there being sliding panels in at 30 least one plane and a hinged panel in at least one of the other planes.

Figures 6 and 11 to 15 are diagrammatic sectional plan views showing similar windows but having panels arranged in four parallel planes.

35 Figure 16 is a vertical section of a metal window having panels arranged in four parallel planes.

Figure 17 is a horizontal sectional plan view of the window of Figure 16 and showing adjacent 40 windows.

Figures 18 and 19 are detail views showing respectively an elevation and vertical section of the runners.

Referring firstly to Figure 1, in one of the 45 planes there are located two panels 1, 2 both of which are mounted to slide; in a second plane there are provided two panels 3, 4 which are also mounted to slide, and in the third plane there are provided three panels 5, 6, 7 of which the panels 5 and 7 are fixed and the panel 6 is hinged at 8 to the panel 5 (or it may be hinged to the panel 7). The window frame is indicated at 9 and is preferably lined with sound-absorbent material 10.

55 Either set of panels may be arranged on the inside of the window, the other being on the outside. Assuming that the panels 5, 6 and 7 constitute the outside panels then the gap between the frame 9 and the sliding panels 1 and 2 may be a permanent one, being on the inside or if on

the other hand the panels 1 and 2 are outside and thus exposed to the weather, there is preferably provided, as shown in dotted lines, a swinging panel 11, which may hinge about its outer vertical edge or about a central pivot. 5

Conveniently as shown the panel 11 may be hinged to the frame 9 on projecting hinges 12 to allow the outside of the panel 11 to be cleaned from the inside.

For ventilation purposes, the panel 6 and also 10 the panel 11, when provided, is opened and in order to obtain the maximum reduction of sound, the sliding panels 1—2, 3—4 are moved to the positions shown, when the sound waves will be caused to take a tortuous path and are arrested 15 or broken up by means of sound absorbing material provided on the side walls of the window frame or alternatively as hereinafter described, in connection with Figure 15, by arranging for the opposing sides, and if necessary also the top and 20 bottom walls to be set at an angle, so that they are out of parallel and thereby preventing transmission of sound by reflection of the sound waves, the latter being reflected externally.

Should it be desired to increase the volume of 25 incoming air and thus the amount of ventilation, the panel 3 may be displaced to the left of Figure 1, when of course the volume of sound will increase due to the shorter path required for the sound waves to enter the room, while still further 30 ventilation can be ensured by sideways movement of the panel 2.

In the modification shown in Figure 2, the panels 1, 2, 3, 4 of Figure 1 are replaced by wider panels 13, 14 and the panels 5, 6 and 7 in Figure 35 1 are replaced by three panels 15, 16 and 17, of which the panels 15 and 17 are hinged and the panel 16 is fixed.

In Figure 3 an arrangement is shown consisting of what is more or less a duplication of the 40 window shown in Figure 2, i. e. there are two sliding panels 13, two sliding panels 14, a hinged panel 15 at each end, two fixed panels 16 and two central hinged panels 17 which can be opened to provide access for cleaning the window or for 45 extra ventilation.

Figure 4 shows an arrangement similar to Figure 3 except that additional narrower width panels 18 and 19 are employed, these panels being 50 slidable as are the panels 13, 13 and 14, 14.

Referring now to Figures 7 to 10, there are illustrated further embodiments of the window of this invention having the panels arranged in three planes.

In these Figures, 7 to 10, sliding panels are indicated by the numeral 20, fixed panels by the numeral 21, panels with projecting hinges by the numeral 22, and panels with ordinary hinges by the numeral 23.

Figures 6 and 11 to 18, illustrate several alter- 60

native constructions of the window, in which there are panels arranged in four planes.

The window of Figure 6, is a development of the form of window shown in Figures 1, 3 and 5 in that, in addition to the intermediate panels 3 and 4 (Figure 1) or 14, 14 (Figures 3 and 5), there are a second set of intermediate sliding panels 19, 19 with the result that the incoming air and thus the sound waves are caused to take 10 an additional bend, before they can pass entirely through the window.

Referring to Figure 11, there is shown a development of the window of Figure 7 wherein an additional intermediate panel 20 is provided.

Figures 12 to 15 illustrate further forms of window in which the sliding panels are indicated by the numeral 20, fixed panels by the numeral 21, panels with projecting hinges by the numeral 22, and panels with ordinary hinges by the numeral 20 23.

In Figures 16 and 17 is shown a metal window having window panels in four planes and comprising two sets of intermediate sliding panels with hinged panels on the inside and outside.

The window on the inside and outside consists of the standard metal window casement type and comprises fixed and moving frames provided with the usual weathering flanges. The fixed frame indicated at 25 is secured in a wood surround 26, and it will be observed that on the inside of the window there two hinged lights 27 and 28, 27 being the larger and main light of the window.

On the outside of the window there is a single hinged casement indicated generally at 29, 30 being the fixed frame thereof in which is fitted an additional fixed light 31. The intermediate and sliding panels indicated respectively at 32, and 33, are formed of plate glass (without frames) and are carried at their lower ends on carriages 40 provided with rollers 34, running on tracks 35, forming part of a fixed frame, the upper and vertical sides of which consist of a U or V shaped strip to provide a groove to receive the edges of the plate.

As shown in Figure 17 the vertical sides of the intermediate frames may be fitted with rubber strip 36 to act as a buffer to cushion the movement of the glass.

It will be observed that the inside vertical walls of the wood surround 26 are set at an angle as indicated at 37 so as to minimise transmission of sound towards the interior by reflection. This may also apply to the horizontal walls. In the case of the lower wall, indicated at 38, the angle is arranged to give to the frame a slope outwardly so that any moisture that may condense, drains to the outside of the window, first collecting in condensation grooves 39, from which are provided ducts 40 leading to the exterior.

The carriage (see Figures 17, 18) consist of an H-section frame, between the upper limbs 41 of which the plate glass is held while the lower limbs 42 serve as a rail guard as can be seen from Figure 19, the connecting web 43 being cut away to receive the roller 34.

The roller 34 is journaled between the limbs 41 upon a bush 44 mounted on a screwed stud 45, which is extended on the inside of the frame to receive a handle piece 46 by which the window is actuated to slide.

The window plate is cut away along its lower edges to accommodate the roller and also to provide space for the fixing putty. To prevent the putty from getting into the bearing, on either side

of the stud 45 are pins 47 around which is fixed a guard strip 48.

The hinged casements 28 may be secured by the usual fastening means which are operable from the inside and in the case of the outside 5 casement access to the fastening is had by shifting the sliding panels to one side. Alternatively, means (not shown) may be provided for operating the hinged panels 11 and 22 on the outside of the window from the inside by means of a control 10 passing through the outer face frame of the window. This may conveniently take the form of a push-pull control of the type known as "Arens" which resembles a large Bowden wire in a casing 15 capable of transmitting power both in tension and compression.

It will be appreciated that in practice the width of the sliding panels is restricted to twice the distance that an arm can reach between the panels.

For the sound deadening material a layer of 20 felt indicated at 49 may be employed. The felt is mounted upon a backing of wood, and its outer surface covered by a layer of American cloth or the like.

What I claim is:

1. A sound reducing window comprising a frame, a plurality of panels collectively of approximately the width of the frame arranged at one face thereof, one of said panels being hinged on a vertical axis to said frame to open outwards, a plurality of panels collectively of approximately the width of the frame parallel to the first mentioned panels, one of the second mentioned panels being hinged on a vertical axis to said frame, and panels disposed in a plane between the first and second mentioned panels slidable horizontally to either side of the frame and being collectively of less width than the frame. 30

2. A sound reducing window comprising a frame, a plurality of panels collectively of approximately the width of the frame arranged at one face thereof, one of said panels being hinged on a vertical axis to said frame to open outwards, the remainder of said panels being horizontally 40 slidable when the hinged panel is open, a plurality of panels collectively of approximately the width of the frame parallel to the first mentioned panels, one of the second mentioned panels being hinged on a vertical axis to said frame, and panels in a plane located between the first and second mentioned panels slidable horizontally to either side of the frame and being collectively of less width than the frame. 50

3. A sound reducing window according to claim 1 wherein the hinged panels are hinged to the same side of the frame, to enable adjustment of the panels to provide a tortuous air passage or a direct air passage through the window space of the frame. 55

4. A sound reducing window according to claim 2 having sound-absorbing material covering the surfaces of the window space of the frame. 60

5. A sound reducing window according to claim 1 having sound absorbing material covering the surfaces of the sides of the frame within the window space consisting of strips spaced apart for entry of the third mentioned panels therebetween, said strips having inclined surfaces exposed in said space to outwardly reflect sound approaching from the outside. 65

6. A sound reducing window according to claim 1 having the surfaces of the frame within the window space canted outwards to reflect sound approaching from the outside. 70
